INVENTOR

Claude S. Van Syckel,

BY
Charles N. Butler
ATTORNEY

UNITED STATES PATENT OFFICE.

CLAUDE S. VAN SYCKEL, OF CAMDEN, NEW JERSEY.

VEHICLE-SPRING.

1,111,278.

Specification of Letters Patent. Patented Sept. 22, 1914.

Application filed January 6, 1914. Serial No. 810,553.

To all whom it may concern:

Be it known that I, CLAUDE S. VAN SYCKEL, a citizen of the United States, residing at Camden, county of Camden, and 5 State of New Jersey, have invented certain Improvements in Vehicle-Springs, of which the following is a specification.

My invention is a vehicle spring adapted for general use but it is intended more particularly for use in automobiles to more effectually absorb shocks and cushion the body.

In its preferred form, my invention consists of a plurality of spring leaves having 15 separated sections converging to a connection with supporting means comprising a lever, and a counter-balancing spring leaf connected with said lever on the opposite side of its fulcrum from the connections of the first 20 named leaves, this lever or equalizer being supported by a link connected with a leaf spring.

A leading object of my invention is to provide a simply constructed spring comprising 25 leaves having separated sections connected in automatically adjustable relation and providing a resilient action over a comparatively wide range of movement to the end that the body may be relieved of shocks 30 communicated through usual spring constructions.

In the accompanying drawings, Figure 1 is a sectional side elevation of mechanism embodying my improvements; and Fig. 2 is 35 a sectional view taken on the line 2-2 of Fig. 1.

The mechanism, as illustrated in the drawings, comprises a vehicle axle 1 on which is fixed a leaf spring 2 by clamping mechanism 3; a body member 4 to which leaves 5, 6, 7, 8, 9, 10, 11 and 12 are fixed by clamping mechanism 13; a hanger comprising the links 14 pivotally connected by a pintle 15 with the end of the leaf spring 2; and an 45 equalizer comprising the levers 16 pivotally connected by the pin 17 with the hanger or links 14, with the leaf 5 by a pintle 18, and with the leaves 8, 9, and 10 by a pintle 19; the leaf 5 having an eye 5' which engages 50 the pintle 18 between the two members 16, and the leaves 8, 9, and 10 having the respective nested eyes 8', 9', and 10' which engage the pintle 19 between the members 16 on the

opposite side of the fulcrum 17 from the 55 pintle 18.

The full leaf 5 is stayed and separated from the full leaf 8 by the short leaves 6 and 7, and the full leaf 10 has thereon the short leaves 11 and 12 which stay the full leaves 8, 9, and 10.

In action, a load is carried from the body member 4 through the separated sections of the leaves 8, 9, and 10 and the counterbalancing leaf 5 to the equalizer 16, and thence through the hanger 14 and leaf spring 2 to 60 the axle, the equalizer having a floating action which permits an automatic adjustment of the relation of the separated sections of the spring leaves 5, 8, 9, and 10, to the end that each shall perform the duty required 70 thereof. Shocks communicated to the axle 1 are transmitted in reverse direction and are absorbed primarily by the parts 2, 5, 8, 9, and 10, stayed by the parts 6, 7, 11 and 12.

Having described my invention, I claim: 75

1. The combination with a vehicle body and axle, of means comprising an equalizer connected with one of said parts, and means comprising a plurality of leaf springs having separated sections and connected with 80 the other of said parts, separated sections of leaf springs aforesaid converging to a connection with said equalizer and a leaf spring aforesaid connected with said equalizer in counter-balancing relation to converging 85 sections aforesaid.

2. The combination with a vehicle axle and body, of a leaf spring connected with said axle, an equalizer connected with said leaf spring, a set of spring leaves connected 90 with said body and having separated sections converging to a connection with said equalizer, and a leaf spring connected with said body, normally separated from said converging sections and connected with said 95 equalizer so as to act in counter-balancing relation to said spring leaves having converging sections.

In testimony whereof, I have hereunto set my name this 26th day of December, 1913, in 100 the presence of the subscribing witnesses.

CLAUDE S. VAN SYCKEL.
